FURNACE STOKER

Herbert E. Preston, Philadelphia, Pa., assignor to
American Engineering Company, Philadelphia,
Pa., a corporation of Pennsylvania

Original application October 3, 1933, Serial No.
691,931. Divided and this application March
6, 1935, Serial No. 9,539

8 Claims. (Cl. 198—226)

This invention relates to improvements in mechanical stokers of the underfeed type, and more particularly to the fuel feeding pushers associated therewith.

5 One object of the present invention is to provide the fuel pushing elements with renewable nose pieces.

Another object is to provide a fuel pushing element of substantially rectangular form having 10 a body portion and laterally adjustable nose pieces to compensate for irregularities in, and wear or growth of the parts.

15 A further object is to provide a fuel pushing element with scraping means provided at the sides and bottom thereof so as to prevent fuel siftings from passing therebetween during operation of the stoker.

Other and further objects will become apparent as the description of the invention progresses.

20 Of the drawings:

Fig. 1 is a longitudinal section of the forward end of a stoker made in accordance with my invention.

Fig. 2 is a plan view of one of the pushers.

25 Fig. 3 is a side elevational view of the pusher shown in Fig. 2.

Fig. 4 is a sectional view taken substantially along line 4—4 of Fig. 2, and

30 Fig. 5 is a sectional end view taken substantially along line 5—5 of Fig. 3.

This application relates more particularly to fuel feeding pushers of underfeed stokers, and is a division of my copending application Serial No. 691,931, filed October 3, 1933, and assigned to 35 the American Engineering Company.

Referring to the drawings, the front framework of the stoker consists, in the present instance, of a plurality of vertical beams 1 supporting a transverse horizontal composite beam 2, which in turn constitutes a support for the forward ends of rearwardly projecting brackets 3, to which are secured the ram boxes 4. The rear ends of the boxes 4 are secured to and supported upon a series of vertical beams 5, which beams also constitute 40 a forward support for the inclined beams 6, which constitute the main supporting frame for the stoker retort structure designated generally in Fig. 1 by the reference numeral 7. In the present instance the bottom of the retorts are composed of a plurality of fixed plates 8 and pusher elements 9, which are adapted for reciprocation between the plates 8 after the manner well understood in the art and illustrated in the drawings. Journaled in the forward ends of the brackets 3 is a main actuating shaft provided with

a series of cranks 13 which through connecting rods 14 are connected with the rams 15 which operate within the boxes 4 in a well known manner to discharge fuel entering the boxes through hopper openings 16 into the upper ends of the retorts. At the extreme upper ends of the retorts and immediately adjacent the mouth of the ram cylinders, the sides of the retorts are provided with replaceable wear plates 10.

At opposite sides of the flange 21 are trunnions 25, which are respectively connected by the short connecting rods 26 with corresponding arms of bell crank levers 27, these levers being mounted one at each side of the ram boxes 4 upon the ends of a shaft 28 journaled in each instance 15 in a bearing 29 depending from said boxes.

The other arms of the bell crank levers 27 are respectively connected through links 31 with the upper ends of bars 32, these bars being connected through a series of bell cranks 33 and links 34 20 with rods 35 connecting, as hereinafter set forth, with the pushers 9. The rods 35 are slidably mounted in guide brackets 36, these brackets being secured in vertical arrangement to the upright beams 5, as shown in Fig. 1. The brackets 36 are flanged and these flanges 37 through which the brackets are secured to the beams, abut one another and thereby close the spaces between the beams 5 to form a wall of the enclosure beneath the retort which constitutes the air box of the 30 furnace into which the draft air is forced, and from which the air passes to the fuel bed through the tuyères 38. The brackets 36 include extensions from both faces of the flanges 37, the inner extensions constituting guides for the rods 35, 35 and the outer projecting portions forming aligned guides for crossheads 39 through which the rods 35 extend, and to the opposite sides of which the links 34 are attached. Those portions of the rods 35 which project through the outer extensions of 40 brackets 36 carry sleeves 41 which constitute sliding bearings for the crosshead 39. The inner end of the sleeve 41 is threaded and receives a nut 42, this nut limiting the relative movement of the crosshead and the sleeve in one direction. 45 The other end of the sleeve is also threaded for reception of a collar 43, which collar is fixed to the extremity of the rod 35 by means of a shear pin 44.

Intermediate the crosshead 39 and the collar 50 43, the sleeve 41 carries an outer sleeve 45, a washer 46 abutting the outer end of this sleeve, and one or a plurality of detachable substantially horseshoe-shaped elements 47, the latter constituting spacing washers which are readily de- 55

tachable for adjustment purposes. The number and width of the washers 47, and the length of the sleeve 45 determine the extent of the lost motion between the sleeve 41 and the crosshead 39, 5 and assuming a given travel of the crosshead 39, the stroke of the rod 35.

The foregoing device provides a ready means for adjusting the stroke of the rod 35 and the pusher 9 associated therewith from the exterior 10 of the furnace, and by means of the operating connection between the crosshead 39 and the shaft 12, and of the adjusting mechanism described above, it will be apparent that the stroke of each of the rods 35 may be regulated independently 15 of the stroke of the others. From the foregoing description, and with reference to Fig. 1, it will be noted that the pushers of the retorts, and the rams respectively associated therewith form operating units, affording a maximum 20 flexibility in the relative adjustment of the various elements of which the unit is constituted.

With reference to Fig. 1, it will be noted that the lowermost of the bell cranks 33 includes a third arm 57 which connects through the medium 25 of the link 58 with the crosshead 39 of the lowermost bracket, and through this crosshead with the lowermost of the rods 35. The uppermost of the rods 35 is connected through a link 59 with the cap pusher 9. The others of the rods 35, 30 with the exception of the bottom, are connected through rods 61 with the respective pushers, the connection between the rods 61 and 35 being in each instance a flexible one by reason of fixtures 62, which are pivotally connected through pins 60 with the inner ends of the rods 35, the fixtures 35 62 also providing for elongating or shortening the overall length of the rods 61.

At its inner end, each of the rods 61 carries a hook 63 which engages and grips a transverse 40 pin 70 in the associated pusher. The connection between the rods 35 and the pushers is accordingly a highly flexible one rendering adjustment and demounting of the various elements a relatively simple one. The lowermost rod 35 is connected through a similar fixture 62 and rod 61 45 through suitable operating connection with an extension grate (not shown).

The details of the pushers 9 are shown in Figs. 2 to 5 inclusive. Each of the pushers comprises 50 a relatively open and light base frame 68 which constitutes the main rear portion of the pusher and which has openings 69 in which the pin 70 is mounted. The frame 68 has a forward extension 71 which constitutes a support for two detachable 55 nose piece sections 72 and 73, these sections, as illustrated, fitting over the extension 71 forming each side thereof and overlapping along a longitudinal center line as indicated at 74 and forming a substantially solid fuel engaging nose 60 for the pushers. The sections 72 and 73 in the present instance are corrugated or toothed at the sides as indicated at 75, this formation in operation giving a desirable scraping action preventing accumulations of finely divided fuel within 65 the retort. The extension 71 of the base frame 68 also has at its forward end and on the under side a transverse recess 76 for a scraper bar which operates upon the tops of the fixed plates 8, as shown in Fig. 1. It will also be noted that each 70 of the fixed plates 8 is provided at the tip with a resilient scraper element 77 which engages and operates upon the top surface of the pusher nose. These last named sections are secured to the pusher frame by means of bolts 78, as illustrated, 75 the device providing a readily detachable and re-

placeable nose for the pushers. The scraper elements tend to prevent siftings of coal dust past the pushers.

As shown more particularly in Fig. 2, the bolts 78 extend through laterally extending elongated slots 80 provided in sections 72 and 73. By this arrangement these sections may be extended laterally into engagement with the retort side walls, thereby compensating for any irregularities in the space between said walls, and also for wear 10 and growth of the parts. The pusher elements 9, therefore, may be adjusted so that at all times they will completely fill the bearing opening, and by virtue of the scraper elements 75 and 77 the passage of siftings past the pusher is reduced to 15 a minimum. This construction also prevents, to a great extent, air leakage into the retorts of the stoker.

While the structures herein described are admirably adapted to fulfill the objects primarily 20 stated, it is to be understood that it is not intended to limit the invention thereto, but only by the scope of claims which follow.

What is claimed is:

1. A stoker pusher, comprising an open base 25 frame, a plurality of overlapping nose pieces secured to said frame, said nose pieces having means extending over the top, sides, and exposed end of said frame, and a plurality of serrations provided along the sides of said overlapping nose 30 pieces.

2. A stoker pusher, comprising a base frame, and a plurality of nose pieces detachably secured to said frame, said nose pieces having means extending over the top, sides, and exposed end of 35 said frame, a plurality of serrations provided along the sides of said nose pieces, and said base having a recess provided in the bottom thereof for receiving a scraping element.

3. A fuel feeding pusher for stokers, comprising 40 a substantially rectangular body portion, and renewable protective elements extending over the top, sides and the exposed end of said body portion, and means for securing said elements to said body portion, said securing means comprising 45 adjustable means, whereby lateral adjustment of said protective elements may be effected.

4. A fuel feeding pusher for underfeed stokers, comprising a substantially rectangular body portion, and renewable protective elements extending over the top, sides and the exposed end of 50 said body portion, scraper means provided at the sides of said protective elements, means for securing said elements to said body portion, said 55 securing means comprising adjustable means whereby lateral adjustment of said protective elements may be effected, and said body portion having a recess provided in the bottom thereof for receiving a scraping element.

5. A protective element, comprising one of the parts of a two-part nose piece for fuel feeding pushers, said element being substantially angular in cross section and consisting of a flat, substantially rectangular top member having a pair 65 of bolt receiving recesses provided therein, a substantially vertical side member, and an end member disposed at substantially right angles to said top and side members, and a flange disposed along the inner edge of said top member, 70 adapted in assembly to overlap with a corresponding flange on the other element of said nose piece.

6. A protective element, comprising one of the parts of a two-part nose piece for fuel feeding 75

pushers, said element being substantially angular in cross section and consisting of a flat, substantially rectangular top member having a pair of bolt receiving recesses provided therein, a substantially vertical side member, and an end member disposed at substantially right angles to said top and side members, a flange disposed along the inner edge of said top member adapted in assembly to overlap with a corresponding flange on the other element of said nose piece, and a series of substantially vertical scraping elements provided on the outer surface of said side member.

7. A base frame for a stoker pusher, said base frame being of substantially rectangular construction and comprising an enlarged portion and a reduced portion, said portions each having a substantially flat upper member and a pair of parallel side members, means provided at one

end of said frame adapting the latter for connection with an operating mechanism, and the lower surface of said frame having a recess for receiving a scraper element.

8. A stoker pusher, comprising an open base frame of substantially rectangular construction, said frame having an enlarged portion and a reduced portion, providing an extended recess at one end thereof, and a pair of renewable protective elements of substantially angular cross-sectional form secured to said reduced portion and neatly occupying said recess whereby the outer surfaces thereof lie in substantially the same planes as the corresponding surfaces of said enlarged portion, overlapping flanges provided on the abutting edges of said protective elements, and a fuel feeding portion provided on each of said elements.

HERBERT E. PRESTON.
